UNITED STATES PATENT OFFICE

JOHN H. HILPMAN, OF HOLLIS, NEW YORK, ASSIGNOR TO MERGENTHALER LINOTYPE COMPANY, A CORPORATION OF NEW YORK

TYPOGRAPHICAL ASSEMBLING MECHANISM

Application filed March 5, 1930. Serial No. 433,235.

This invention relates to typographical composing machines, such as linotype machines of the general organization represented in Letters Patent of the United States No. 436,532, to O. Mergenthaler, wherein circulating matrices are released from a magazine in the order in which their characters are to appear in print and then assembled in line, the composed line transferred to the face of a mold, the mold filled with molten metal to form a slug or linotype against the matrices which produce the type characters thereon, and the matrices thereafter returned through distributing mechanism to the magazine from which they started. In these machines, the matrices when released from the magazine pass down or through a vertical channeled raceway or front plate, and onto the upper stretch of an inclined endless conveyor belt, from which they pass through a guide throat or chute to an assembler, wherein they are composed in line under the influence of a rotary star wheel.

As ordinarily constructed, the assembler throat is constituted at its lower side by a pair of so-called "assembler rails", which partially enclose the star wheel and upon which the matrices are discharged by the conveyor belt, and at its upper side by a so-called "chute spring", which is arranged to engage the side faces of the matrices and confine them to their proper path of travel through the throat. The chute spring is usually attached to a fixed part of the machine with its lower end located at a given distance from the assembler rails, such distance being chosen so as to provide for the proper guidance of the thinner matrices and to allow the spring to yield in guiding the thicker matrices. Although the matrices passing under the control of the chute spring are caused to follow the curvature of the rails until they engage the star wheel, it is also important that they be further guided and restrained against upward movement as they pass from under the chute spring into engagement with the star wheel, the action of the latter at this moment tending to project the matrices upwardly as well as forwardly. Hence, the chute spring is usually

formed at its lower end with a pair of horizontally disposed prongs, which are intended to hold the matrices down as they are about to enter the assembler.

In practice, however, it has been found that the aforesaid chute spring is incapable of efficiently handling matrices above a certain thickness, for the reason that the extent of the displacement of the spring by the extremely thick or head-letter and display matrices is so great that the horizontally disposed prongs either fail to function at all or snap down upon the upper ends of the matrices as they clear the spring and thus interfere rather than assist in their assemblage. It has also been necessary, in machines equipped with the larger matrix fonts, to file clearance notches in the spaceband channel, which happens to terminate at its lower end immediately above the chute spring. Furthermore, another and probably the most serious objection comes from the frequent clogging or piling up of the matrices in the assembler throat because of the undue resistance offered by the chute spring to the thicker matrices and the consequent delay in their passage to the assembler. In an endeavor to overcome the latter difficulty, the chute spring is usually mounted so that it can be manually adjusted to different operative positions and in this way vary the width of the assembler throat to correspond to the different matrix fonts, but owing to the fact that the matrices in some of the more recent individual fonts vary widely in the thickness, the liability to clogging has not been entirely eliminated.

The present invention is intended to overcome the foregoing and other objections, and contemplates a chute spring which will offer a minimum resistance to the descending matrices and which will guide them properly both through the throat and into the assembler without regard to their size or font. To this end, the improved chute spring, in the preferred embodiment illustrated, consists of a pivoted member presenting a pair of spaced arms or flanges arranged to guide the thicker matrices solely by their projecting ears. Associated with said member is an elongated flexible spring extending down-

wardly from a fixed support and arranged to guide the thinner matrices by their side faces, as distinguished from their ears. At their lower ends, the ear-engaging arms or flanges of the pivoted member are beveled off horizontally to present a pair of extended guiding edges corresponding to the horizontally disposed prongs of the old chute spring, but inasmuch as the arms escape contact with the body portions of the matrices and since the matrix ears which they engage vary but slightly in thickness, these lower guiding edges are allowed to maintain their proper matrix guiding position and hence function in a more reliable manner.

In the accompanying drawings, the invention is shown merely in preferred form and by way of example, but obviously many changes and variations may be made therein and in its mode of application which will still be comprised within its spirit. It should, therefore, be understood that the invention is not limited to any specific form or embodiment, except insofar as such limitations are specified in the claims.

Referring to the drawings:

Fig. 1 is a front elevation of the lower portion of a linotype machine with the present improvements applied thereto;

Fig. 2 is an enlarged front view of the assembling devices immediately concerned with the present improvements;

Fig. 3 is an edge view looking from the left in Fig. 2, with certain parts removed in order to show more clearly the improved construction;

Fig. 4 is a view similar to Fig. 2, but showing the improved chute spring guiding a matrix with offset ears; and

Fig. 5 is a perspective view of the improved chute spring detached.

The matrices X (see Fig. 1) are stored in the magazine A and are released therefrom by the manipulation of the keyboard B, whence they pass downwardly through a channel raceway or front plate C onto a constantly driven inclined conveyor belt D, which discharges them one after another in the order of their release into a throat E leading to the assembling elevator F. Here they are composed in line with spacers Y under the influence of a star wheel G, and the line thereafter delivered to the casting mechanism, all as is well understood in the art.

The matrices X are formed as usual with upper and lower projecting ears z, which are generally located at one side of the individual matrices, and that side during composition is the rear or following one. When therefore, the matrices are delivered to the conveyor belt, they will lie upon their rear sides, and their projecting ears (which themselves vary but slightly in thickness) will pursue the same path to the assembler throat without regard to the thickness of the matrices. However, in

some of the matrix fonts now in use, and for reasons well-known to the art, certain of the thicker matrices are "back-milled", or, in other words, have their projecting ears spaced or offset somewhat from their rear side faces (see the matrix shown in Fig. 4). This condition is also true in the case of the fifty-five character fonts employed in the model 21 commercial machines or as described in the Kennedy Patent No. 1,397,967. The chute spring herein proposed and which, as before stated, cooperates with the projecting ears of the matrices is intended to serve equally well in handling both the regular and "back-milled" matrices.

As best shown in Fig. 5 the improved chute spring or guide member J presents a pair of spaced side arms or flanges J¹ and an intermediate connecting strap portion J² arranged at the upper ends of the arms. In the form shown, the guide member is made of sheet metal, stamped out in the flat, and then bent to shape, the cost of manufacture thereby being reduced to a minimum.

When the guide member J is applied to the machine, the arms J¹ thereof are adapted to overlie the curved assembler rails E¹ in such relation thereto as to constitute the upper side of the throat E, the lower edges j of the arms being disposed in close spaced relation to said rails (which constitute as usual the bottom side of the throat) and being curved throughout the greater portion of their length with the curvature diverging generally upward from the lower ends of the arms away from the assembler rails.

In the present instance, the guide member J is pivotally mounted at its upper end on a fixed bearing pin J³ so as to permit the depending arms J¹ thereof to be pushed or swung aside by the matrices of the "back-milled" type and, at the same time, offer when necessary a yielding resistance to the regular matrices, whose projecting ears may happen to strike the lower edges of the arms. The guide member J is located in its normal position by means of a stop pin J⁴, which is arranged adjacent the bearing pin J³ in engaging relation to a lug or horn J⁵ projecting downwardly from the strap portion J².

When the horn J⁵ is engaged with the stop pin J⁴, the lower ends of the arms J¹ will be sustained in spaced relation to the assembler rails E¹ at a distance determined by the matrix ears of the maximum thickness, so that all matrices of regular form may pass freely through the throat without appreciably disturbing the position of the guide member, it being understood that the projecting ears of the matrices lie in the vertical planes of the arms J¹ while their body portions are disposed between the arms and are therefore free to project up through them without regard to thickness. However, under ordinary assembling conditions, the matrices are de-

livered to the throat at quite a high rate of speed and their momentum is such that, as they take the curve of the throat, the suspended weight of the guide member J might be insufficient to maintain the arms J¹ in their 5 normal position against the sudden shocks of the descending matrices. Consequently, to give the guide member the required resiliency, it is provided with a light wire spring J⁶, which (as best shown in Fig. 3) is coiled 10 around the bearing pin J⁸ with one of its ends pressing against the connecting strap portion J² and its other end reacting against the stop screw J⁴.

The arms J¹ at their lower ends terminate 15 in a predetermined distance above the star wheel G and, as will be noted from Fig. 2, present straight horizontal guiding edges j¹ which are adapted to cooperate with the upper ends of the matrices as they pass into engagement with the star wheel. These guiding edges j¹ act to resist the impulses of the star wheel which tend to thrust the matrices upwardly and forwardly, and in this way 20 greatly facilitate the assemblage of the matrices in line. Moreover, since the matrices are guided by their projecting ears rather than by their side faces during their passage through the throat E, the displacement of 25 the arms J¹ is relatively slight, so that the guiding edges j¹ are allowed to maintain their proper relation to the matrices at all times after the correct position of the member J is once established.

The "back-milled" matrices before referred to, because of the higher location of their projecting ears, will of course displace the arms J¹ to a slightly greater extent than the regular matrices, but such displacement 30 is still relatively small as shown in Fig. 4, and hence these matrices will also be properly restrained against abnormal upward movement and so directed into the line properly and without delay or undue vibration.

The guide member J is intended more particularly to handle matrices above a certain thickness, altho it is also capable of handling a majority of the thinner ones. Many of these latter matrices, however, (those ranging in thickness, say, from a minimum of .020 to .030 of an inch) are so light in weight that their behavior under the guiding action alone of the member J might be somewhat uncertain. For this reason, in carrying out the 45 invention, supplementary means are provided for guiding these extremely thin matrices through the throat E independently of the guide member J. Such means (as best shown in Figs. 2 and 3) consist of a thin, flexible leaf spring K secured to one of the guide plates of the raceway C at a considerable distance above the guide member J, and which extends downwardly below the latter 50 to a point adjacent the lower ends of the arm

J¹. The spring K is adapted to cooperate with the top or front side faces of the matrices, being disposed normally in a position above the assembler rails E¹ at a distance therefrom determined by the thickness of the thinnest matrix, and being narrow enough to clear the inner walls of the arms J¹ when it is displaced by the thick matrices. As thus arranged, the very thin matrices will be gradually straightened out by the spring K as 70 they enter the throat E and then be held thereby lightly engaged with the assembler rails E¹ until they emerge from the throat. At this time, they are subjected to the action of the star wheel G before described but, like 75 the thicker matrices, will be properly guided into the assembler F by the straight horizontal edges j¹ at the lower ends of the arms J¹.

While the spring K permits the free and 80 unretarded passage of the thin matrices through the throat E, the slight resistance offered thereby to the thick matrices is advantageous rather than harmful, since it tends to break the fall of such thick matrices 85 and assists in guiding them along the assembler rails by the arms J¹.

Having thus described my invention, what I claim is:

1. Typographical assembling mechanism 95 for handling matrices of different thicknesses formed with projecting ears and including, in combination, an assembler wherein the matrices are composed in line, a conveyor belt for delivering matrices to the assembler, 100 rails leading from the discharge end of the belt to the entrance of the assembler, and guiding means for confining the matrices to their proper path of travel as they pass along said rails, said means including a pair of 105 flanges for guiding the matrices above a certain thickness by their projecting ears, and subsidiary means associated with said flanges and arranged in closer proximity to the rails for guiding the thinner matrices by their side 110 faces.

2. Typographical assembling mechanism for handling matrices of different thicknesses formed with projecting ears and including, 115 in combination, an assembler wherein the matrices are composed in line, a conveyor belt for delivering matrices to the assembler, rails leading from the discharge end of the belt to the entrance of the assembler, and guiding means for confining the matrices to their proper path of travel as they pass along said rails, said means including a resilient member for guiding matrices above a certain thickness by their projecting ears, 120 and a thin flexible leaf spring associated with said member for guiding the thinner matrices by their side faces.

3. Typographical assembling mechanism for handling matrices of different thicknesses formed with projecting ears and including, 125 in

combination, an assembler wherein the matrices are composed in line, a conveyor belt for delivering matrices to the assembler, rails leading from the discharge end of the belt to the entrance of the assembler, and guiding means for confining the matrices to their proper path of travel as they pass along said rails, said means including a pair of flanges for guiding matrices above a certain thickness by their projecting ears, and a thin flexible leaf spring associated with said flanges for guiding the thinner matrices by their side faces, said guiding flanges being formed at their lower ends with horizontally disposed guiding edges for engaging the upper ends of both the thin and thick matrices as they enter the assembler.

4. Typographical assembling mechanism for handling matrices of different thicknesses formed with projecting ears and including, in combination, an assembler wherein the matrices are composed in line, a conveyor belt for delivering matrices to the assembler, rails leading from the discharge end of the belt to the entrance of the assembler, and guiding means for confining the matrices to their proper path of travel as they pass along said rails, said means including a guide member resiliently mounted and presenting two side arms or flanges overlying the rails for guiding matrices above a certain thickness by their projecting ears, and subsidiary means associated with the flanges for guiding the thin matrices by their side faces, said flanges being formed at their lower ends with horizontally disposed guiding edges for engaging the upper ends of both the thin and thick matrices as they enter the assembler.

5. Typographical assembling mechanism for handling matrices of different thicknesses formed with projecting ears and including, in combination, an assembler wherein the matrices are confined in line, a conveyor belt for delivering matrices to the assembler, rails leading from the discharge end of the belt to the entrance of the assembler, and guiding means for confining the matrices to their proper path of travel as they pass along said rails, said means including a thin flexible leaf spring for guiding the matrices by their side faces, and guiding means mounted independently of said spring for engaging the matrices at their upper ends as they enter the assembler.

55. 6. Typographical assembling mechanism for handling matrices formed with projecting ears and including, in combination, an assembler wherein the matrices are composed in line, a conveyor belt for delivering matrices to the assembler, rails leading from the discharge end of the belt to the entrance of the assembler, and means resiliently mounted for guiding the matrices by their projecting ears as they pass along said rails.

55. 7. Typographical assembling mechanism

for handling matrices formed with projecting ears and including, in combination, an assembler wherein the matrices are composed in line, a conveyor belt for delivering matrices to the assembler, rails leading from the discharge end of the belt to the entrance of the assembler, and a matrix guide member presenting two side arms or flanges overlying the rails and arranged in position to engage the projecting ears of the matrices, said guide being pivotally mounted to permit temporary displacement of the side arms thereof by the passing matrices, for the purpose described.

8. Typographical assembling mechanism for handling matrices formed with projecting ears and including, in combination, an assembler wherein the matrices are composed in line, a conveyor belt for delivering matrices to the assembler, rails leading from the discharge end of the belt to the entrance of the assembler, a pivoted guide member presenting a pair of depending side arms or flanges overlying the rails for guiding the matrices by their projecting ears, and a spring for holding the guide member resiliently in operative position.

9. Typographical assembling mechanism for handling matrices formed with projecting ears and including, in combination, an assembler wherein the matrices are composed in line, a conveyor belt for delivering matrices to the assembler, rails leading from the discharge end of the belt to the entrance of the assembler, a pivoted guide member presenting two side arms or flanges overlying the rails for guiding the matrices by their projecting ears, a stop pin for locating the guide member in operative position, and a spring for holding the guide member resiliently engaged with the stop pin.

10. Typographical assembling mechanism for handling matrices formed with projecting ears and including, in combination, an assembler wherein the matrices are composed in line, a conveyor belt for delivering matrices to the assembler, rails leading from the discharge end of the belt to the entrance of the assembler, and a matrix guide member presenting two side arms or flanges overlying the rails and arranged in position to engage the projecting ears of the matrices, said guide member being mounted so as to permit temporary displacement of the side arms thereof by the passing matrices, and the said arms being formed at their lower ends with horizontally disposed guiding edges for engaging the matrices at their upper ends as they enter the assembler.

11. Typographical assembling mechanism for handling matrices formed with projecting ears and including, in combination, an assembler wherein the matrices are composed in line, a conveyor belt for delivering matrices to the assembler, rails leading from the

discharge end of the belt to the entrance of the assembler, and a matrix guide member presenting two side arms or flanges overlying the rails and arranged in position to engage
5 the projecting ears of the matrices, said guide member being pivotally mounted to permit temporary displacement of its side arms by the passing matrices, and the said arms having their lower edges curved throughout the
10 greater portion of their length and formed at their lower ends with straight horizontally disposed guiding edges, substantially as shown and described.

12. In or for a typographical assembling
15 mechanism, a matrix guide member presenting a pair of depending side arms whose lower edges are adapted to guide the matrices by their projecting ears and formed at their lower ends with horizontally disposed guiding edges to cooperate with the upper ends
20 of the matrices.

13. A matrix guide member according to
claim 12, characterized by the fact that the
lower ear-engaging edges of the side arms are
25 curved throughout the greater portion of
their length.

14. A matrix guide member according to
claim 12 made from a sheet metal stamping
bent to shape.

30 15. A sheet metal matrix guide member
presenting two parallel spaced side arms or
flanges and an inverted U-shaped web portion
connecting said arms at their upper ends,
leaving the space between the arms open at
35 both sides throughout the length of the arms.

16. A guide member according to claim 15
characterized by the fact that the connecting
web portion is formed with a bearing
opening to receive a pivot pin on which the
40 guide member is to be mounted.

17. A guide member according to claim 15
characterized by the fact that the connecting
web portion is formed with a projecting piece
to act as a stop for the guide member when
45 mounted pivotally in the machine.

In testimony whereof, this specification
has been duly signed by:

JOHN H. HILPMAN.
